JAR

John B. Smurr, San Francisco, Calif., assignor to
Hazel-Atlas Glass Company, Wheeling, W. Va.,
a corporation of West Virginia

Application June 28, 1949, Serial No. 3,604

Term of patent 14 years

(Cl. D58—25)

To all whom it may concern:

Be it known that I, John B. Smurr, a citizen of the United States, residing at San Francisco, in the county of San Francisco and State of California, have invented a new, original, and ornamental Design for a Jar, of which the following is a specification, reference being had to the accompanying drawing, forming part thereof.

Figure 1 is a front elevational view of a jar, showing my new design;

Figure 2 is a side elevational view thereof;

Figure 3 is a top plan view thereof; and

Figure 4 is a horizontal sectional view thereof, taken on line 4—4 of Figure 1.

I claim:

The ornamental design for a jar, as shown.
JOHN B. SMURR.
